UNITED STATES PATENT OFFICE

2,432,751

BREAKER STRIP STRUCTURE FOR SPACED
WALL CABINETS

Martin J. Goulooze, Grand Rapids, Mich., assignor to Nash-Kelvinator Corporation, Detroit, Mich., a corporation of Maryland

Application April 20, 1942, Serial No. 439,617, which is a division of application Serial No. 402,900, July 18, 1941. Divided and this application June 22, 1944, Serial No. 541,630

1 Claim. (Cl. 220—9)

1

The present invention relates to refrigerating apparatus, and more particularly to refrigerator cabinet construction.

The present application is a division of abandoned application Serial No. 439,617, filed April 20, 1942, which is in turn a division of application Serial No. 402,900, filed July 18, 1941, and now matured into Patent 2,329,755.

An object of the present invention is to provide relatively thin gauge metallic breaker strips of low heat conductivity for interconnecting the inner and outer walls of a refrigerator cabinet, and to arrange for securing said breaker strip to said walls in an improved manner.

It is a further object of the present invention to provide for the assembly of the cabinet whereby its internal and external wall surfaces are free of projecting or visible affixing means, such as screw heads or the like.

The invention itself, however, both as to its organization and its method of operation, together with additional objects and advantages thereof, will best be understood from the following description of specific embodiments when read in conjunction with the accompanying drawings.

In the drawings:

Figure 1 is a front view of a refrigerator cabinet with parts broken away; and

Figure 2 is a cross sectional view through a portion of a wall of the cabinet and door.

Shown in the drawing is a refrigerator cabinet 20 having a food storage compartment 22. Access opening 25 to the food storage compartment is closed by a pivotally mounted door 26. The compartment 22 is formed by a liner or inner shell 175 having side, top, bottom and rear walls. The edges of the side, top and bottom walls around the opening 25 are marginally flanged outwardly at right angles to form a portion of the front wall of the cabinet, as at 174. The marginal edge of the flange 174 is in turn bent at right angles to extend rearwardly parallel to the wall of the liner, as at 180.

Extending spatially about the liner 175 is an outer casing or shell 170 comprising top and side walls formed as a unitary structure rolled from a single sheet of metal. The forward marginal edge of the shell is bent at right angles to extend inwardly peripherally about the door opening 25 to form a front wall section 173. The front wall 173 is of double wall thickness with the metal doubled back upon itself and continuing along the side wall 170 a determinable distance, and then turned at right angles in spaced parallel extension to the doubled wall 173 as at 171.

In the form shown the outer shell or casing 170 is formed with a pocket 172 rearwardly of the

double thickness front wall 173. The front wall is set inwardly of the front wall portion 174 of the liner 175. The wall 174 is inclined to be in planular alignment with the pocket 173. The wall 174 is flanged to extend rearwardly parallel to side wall of the liner, as at 180. A breaker strip 176 extends in joining the walls 173 and 174, one end of which is looped, as at 177, and lies within the pocket 172. The opposite end 181 extends over the face of the front wall 174 to be reversely bent and extending rearwardly, thence upwardly along the flange 180 to be turned over its end downwardly, as at 182.

The breaker strip 176 is of a flexible relatively thin metallic sheet having a thickness preferably not exceeding .010 of an inch, and is preferably formed of stainless steel though it may be formed of other material and suitably coated with enamel or it may plated.

20. What I claim is:

A cabinet construction comprising an outer casing having a portion forming a front wall and having a portion extending in back of said front wall for forming a pocket therebetween, an inner liner disposed within the casing in spaced relation thereto and being provided with an inclined front wall extending outwardly from the liner, said inclined front wall being in alignment with the pocket, and having a flange extending therefrom parallel to the side wall of the liner, a thin resilient metallic breaker strip extending between said outer casing and liner and having one end thereof reversely bent to provide a loop, said loop end of said breaker strip extending into said pocket of the casing and resiliently engaging the walls of said pocket, said breaker strip having the opposite end thereof reversely bent upon itself in a direction toward said outer casing and engaging the inclined wall of said liner, and then bent rearwardly and parallel to said flange of said liner for engagement therewith for securing the breaker strip to said front walls of said casing and liner.
